INTERNAL COMBUSTION ENGINE

Filed Sept. 26, 1925

UNITED STATES PATENT OFFICE

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN

INTERNAL COMBUSTION ENGINE

Application filed September 26, 1925. Serial No. 58,681.

This invention relates to internal combustion engines and particularly to the lubrication system of large heavy-duty engines, such as are used in the propulsion of air-craft.

Such engines are frequently operated for long periods at full load, under severe conditions which make a replenishment of the lubricating oil impossible, and it is, therefore, essential that an ample supply of lubricant be carried. Furthermore, these engines are frequently inclined at steep angles to the horizontal, as in climbing and diving, and are maneuvered into other unusual positions, even to the extent of being required to function for short periods in an inverted position. These requirements have led to an extensive use of the dry sump type of lubrication system, in which the oil drained into the crankcase from the various bearings is pumped by a scavenging pump into a storage tank or reservoir. In this way no considerable amount of oil is present in the oil pan or sump at any time so that the danger of flooding the engine cylinders when the engine is inclined at an extreme angle is materially decreased. Oil is pumped by a separate pump from the reservoir to the points to be lubricated.

This system, however, is subject to the disadvantage of requiring a separately mounted oil reservoir, which must be connected to the engine by additional exposed piping, and it furthermore requires more than one pump.

One of the objects of the present invention is to provide an internal combustion engine of the dry sump type, having an oil storage reservoir which is an integral part thereof.

Another object of the invention is to provide such a storage reservoir which does not require exposed connections, and to which oil is drained from the engine sump by gravity.

Another object of the invention is to provide such a reservoir from which the back flow of oil into the crankcase will be relatively slow even when the engine is tilted at extreme angles, and to which such back flow will be prevented when the engine is completely inverted.

A further object of the invention is to provide a lubricating system for such engines in

which a dry sump is obtained with the use of a single pump.

Other objects of the invention will appear from the following description taken in connection with the drawing, which forms a part of this specification, and in which:

Fig. 1 is a view, partially in side elevation and partially in longitudinal section, through an engine constructed in accordance with this invention;

Fig. 2 is a view in section substantially on the line II—II of Fig. 1, and

Fig. 3 is a view, similar to Fig. 2, showing the engine in an inverted position.

Referring to the drawing, at 10 is shown an internal combustion engine having a crankcase 11 upon which are mounted a number of cylinders 12 of any desired construction. The engine is provided with a crank shaft 13, which is connected by the usual connecting rods to pistons adapted to operate within the engine cylinders 12. Suitably secured to the bottom of the crankcase 11 in any convenient manner, as by the bolts 14, is an oil pan or lower crankcase portion 15, the bottom of which forms a sump 16 adapted to receive oil which overflows from the engine bearings in a manner well understood in the art to which this invention relates.

Integral with, or otherwise suitably secured to the oil pan 15 is a second oil pan 17 arranged beneath the pan 15 and adapted to form therewith a double bottom for the crankcase 11. The pan 17 defines, in conjunction with the bottom of pan 15, a space which constitutes an oil storage tank or reservoir 18. This reservoir 18 is constructed of dimensions such as to contain an ample supply of oil for a run of any desired duration.

Depending from the bottom of the pan 15 and integral with, or otherwise suitably secured thereto, are a number of drain conduits 19 which extend into the reservoir 18 preferably nearly to the bottom or floor thereof. A number of these conduits 19 are disposed along the central portion of the pan 15 and are arranged at the lowest points of said pan, to provide ready drainage by gravity of any oil which may be deposited in the sump 16.

from the engine bearings and other points lubricated. It will be apparent that by spacing the conduits 19 along the center line of the sump 16, the oil deposited within this 5 sump will be drained through one of these conduits even when the engine is quite sharply inclined to the horizontal.

The lower oil pan 17 may be conveniently formed at one end with a depressed portion 10 21, in which a drain plug 22 is located, and is preferably formed at the other end with a flange 23 defining an opening which is covered by a pump housing 24. The housing 24 is adapted to contain an oil pump of any 15 suitable construction (not shown) which may be conveniently driven from the engine, as by means of a vertical shaft 25 adapted to pass through the pans 15 and 17. The pump is provided with the usual intake pipe 26, 20 which passes into the oil reservoir 18 and preferably extends along the bottom of the lower pan 17 to about the middle thereof, as clearly shown in Fig. 1. A delivery pipe 27 leads from the pump housing 24 to the lubrication system of the engine in the well-known manner.

The general oil level within the engine upon a steep inclination thereof to the front or to the rear, such as would be obtained in a glide 30 or in a climb, is indicated by the dotted lines A.A and B.B respectively of Fig. 1. It will be noticed that the end of the suction pipe 26 of the pump will in either event be submerged in oil, so that the pump will deliver oil to the engine even under the more severe conditions of diving or climbing which it will normally be called upon to perform.

In Fig. 3 is illustrated the portion of the oil level in the reservoir 18 when the engine is 40 inverted, a condition which may obtain for very short intervals of time, as when the engine is mounted in an airplane which is performing a loop or some similar maneuver. It will be apparent that the oil level in this 45 case lies below the ends of the conduits 19, so that there will be no appreciable return flow of oil through the conduits 19 into the sump 16. Accordingly, flooding of the engine cylinders with a large volume of oil does not 50 obtain under these conditions.

In performing certain maneuvers the engine may be placed in a position in which its crankshaft is vertical or nearly so. This 55 may occur, for example, in a nose dive or in a stall, and while in this position a certain amount of oil will flow back from reservoir 18 through the conduits 19 into the crankcase. The size of the conduits 19 is however 60 so small and the possible duration of such positions of the engine is so short, that a back flow of oil sufficient to flood the crankcase cannot occur.

The operation of this invention will be 65 clear from the foregoing description. It is obvious that by it is provided an engine hav-

ing a single pump dry sump system of lubrication, and in which all the advantages of a large oil reservoir are obtained without duplication of the pumping apparatus, and without excessive oiling in any position into which the engine may be placed.

It will be understood that various forms of the invention other than those described above may be used without departing from the spirit or scope of the invention.

Having thus described the invention, what is claimed and desired to secure by Letters Patent is:

1. The combination in an internal combustion engine having a crankcase and an oil sump therefor, of an oil reservoir, a plurality of open conduits connecting said sump with said reservoir and adapted to drain the sump when the engine is steeply inclined, and a pump associated with the reservoir and adapted to supply oil therefrom to the engine at any angle of inclination of the engine at which said conduits will drain the sump.

2. The combination in an internal combustion engine having a crankcase and an oil sump therefor, of an oil reservoir, open conduits adapted to drain all oil from said sump into said reservoir at all normal angles of inclination of the engine and to prevent substantial back-flow of oil when the engine is inverted, the ends of said conduits in the reservoir extending adjacent the bottom thereof, and a single pump to supply oil to the engine having its intake in the middle of the reservoir.

3. The combination, in an internal combustion engine, having a crankcase provided with a bottom defining a sump, and a second bottom defining an oil storage space with said first bottom, of a plurality of open conduits connecting said sump and space, said conduits being associated with the first bottom to substantially empty said sump and to retard the back flow of oil from the space to the sump, whereby flooding of the engine in any position of inclination is prevented.

4. In combination in an internal combustion engine having a crank case provided with a flat bottom defining a sump and a second flat bottom below and parallel with the first bottom defining an oil storage space, a conduit extending from the sump into the oil storage space at substantially the center thereof, an open conduit extending from the sump into the oil storage space adjacent each end thereof, one end of said conduits being flush with the inner face of the bottom defining the sump and the other end of said conduits terminating adjacent the inner face of the second bottom, and a suction conduit leading from the storage space, said suction conduit terminating beneath the central conduit and adjacent the second bottom.

5. The combination in an internal combus-

tion engine having a crank case, of a double bottom for said crank case defining a sump and a storage space, a plurality of open drain conduits arranged longitudinally of the engine and secured to the upper bottom, one end of said conduits being open to the sump and the other end of said conduits extending adjacent the lower bottom within the storage space, and a suction outlet conduit extending into the storage space, said outlet conduit having an open end arranged centrally of the space and adjacent the lower bottom.

6. The combination in an internal combustion engine for aeroplanes having a crank case, of a double bottom for said crank case comprising a pair of spaced oil pans defining an oil space therebetween, and a plurality of unrestricted drain conduits extending through the upper pan and downwardly into said space, said conduits being longer than the depth of oil in the space when the engine is inverted and open to the crank case to drain all oil therefrom at all normal angles of engine inclination.

25 In testimony whereof I affix my signature.
LIONEL M. WOOLSON.
